[57] **CLAIM**

The ornamental design for a lace lock for a shoe, as shown and described.

DESCRIPTION

FIG. 1 is a side elevational view of a lace lock for a shoe showing my new design;

FIG. 2 is a side elevational view of a lace lock for a shoe showing a modified form of my new design, said form being a mirror image of the first embodiment; and, FIG. 3 is a cross-sectional view taken along section 3—3 in FIG. 2.

The broken line showing of the upper and sole in FIGS. 1 and 2 is for illustrative purposes only and forms no part of the claimed design.
